DESIGN FOR A DRESS

Michael Gregory Stein, Brooklyn, N. Y.

Application June 5, 1944, Serial No. 113,860

Term of patent 3½ years

(Cl. D3—26)

To all whom it may concern:

Be it known that I, Michael Gregory Stein, a citizen of the United States, residing at Brooklyn, New York city, in the county of Kings and State of New York, have invented a new, original, and ornamental Design for a Dress, of which the following is a specification, reference being made to the accompanying drawing, forming a part thereof.

Fig. 1 is a front view of a dress showing my design, the neckline being in open position;

Fig. 2 is a view similar to Fig. 1 with the neckline in closed position; and

Fig. 3 is a rear view of the dress shown in Fig. 1 on a reduced scale.

I claim:

The ornamental design for a dress, as shown.
MICHAEL GREGORY STEIN.
